MATCH BOOKING MACHINE

Wilmer C. Nicodemus, Barberton, Ohio, assignor
to The Diamond Match Company, New York,
N. Y., a corporation of Delaware

Application June 7, 1939, Serial No. 277,849

10 Claims. (Cl. 93—2)

This invention relates to match booking machines, and more particularly to a machine of the type embodying mechanism whereby flexible covers are successively positioned in the active path of an oscillating blade which is effective to fold each cover and insert it in an intermittently movable carrier by means of which the folded covers are borne progressively to match assembling and other mechanisms. A machine of the type referred to is disclosed in United States Patents No. 1,042,472, dated October 29, 1912; No. 1,479,481, dated January 1, 1924; and No. 1,836,496, dated November 8, 1932, to which patents reference may be had.

The principal object of my invention is to provide simple and efficient means for folding each succeeding cover in a manner to present at the closed end thereof a flat friction bearing base of the character described in Patent No. 2,101,111, dated December 7, 1937, and also for inserting within the fold a strip of material which reinforces the base and obviates liability of the outward bowing of the base by opposing pressure on its longitudinal edges during the normal use of the finished match book, particularly when the cover is of relatively thin or soft pasteboard.

With this object in view my invention comprises novel features of construction and combinations of parts which in a preferred embodiment of my invention will be hereinafter described; the scope of the invention being expressed in the appended claims.

In the drawings—

Figure 1 is a transverse section of the cover inserting end of a match booking machine equipped with cover-folding mechanism and reinforcing-strip feeding and inserting mechanism embodying my invention in a preferred form.

Fig. 2 is a sectional plan of the said mechanisms.

Fig. 3 is a front elevation, partly in section, of a portion of the booking machine and the associated mechanisms.

Fig. 4 is a transverse vertical section, as on the line 4—4 of Fig. 3.

Fig. 5 is a sectional detail of feeding and glue applying rolls for a web of reinforcing material, showing the bed and the cover folding devices including a forming plunger, the leading section 50 of the said material being represented as overlying the cover and severed by the plunger.

Fig. 6 is a similar section of the throat of the channeled folding member and the acting end of the plunger, the latter being represented in its 55 initial descent within said member and the folded

cover and the contained reinforcing strip being shown.

Fig. 7 is a perspective view of the web slitting mechanism; a portion of a web as transversely slit to define reinforcing sections; glue applying disks, and a portion of the forming plunger.

Fig. 8 illustrates the transversely slitted end portion of the web.

Fig. 9 is a perspective view of a complete match book having a folded and reinforced base portion 10 exteriorly coated with ignition material.

Referring to the annexed drawings, 15 designates the supporting frame including the table 16 of a match booking machine; 17 designates a chain of pocketed links constituting an intermittently-movable carrier whereof the upper run is guided in a trough 18 on the table, and 19 designates the driven cam shaft which, through suitable cam and transmission mechanisms, actuates the carrier and other moving parts of 20 the machine.

Spaced cover-containing magazines 20 are supported by brackets 21 on the table, and horizontal chambered slides 22, which are mounted in guideways in the respective brackets, constitute bottoms for the magazines. The top of each slide is provided with a perforated area 23 and the chamber of the slide is connected at one end by means of a flexible tube 24 in controllable communication with a suitable pump (not shown), whereby air is periodically removed from the chamber and the lowermost cover (C) in the magazine is thus held flatwise upon the perforated area. Hence by reciprocating the slide to move such area under and beyond the magazine each succeeding lowermost cover is removed from the magazine, the respective ends of the cover projecting beyond the slide, as seen in Fig. 4.

In the present instance means for simultaneously actuating the slides comprises a pair of levers 25 which are suitably mounted beneath the table and are jointed at their upper ends to the respective slides, the lower ends of the levers being equipped with rolls 250 which run in peripherally grooved cams 26 on the shaft 19. (See 45 Fig. 1.)

Channeled folding members 27 are supported on the inner sides of the respective brackets 21. In each member is formed from top to bottom a curved channel 28 whereof the outer side is open 50 and the top is directly below the adjacent cover when it is withdrawn from the magazine by the "suction" slide 22. Curved folding blades 29 corresponding with the respective channels of the members 27 are arranged and adapted to swing 55

into and from the channels. Each blade in its downward stroke engages the opposing end portion of the cover and tucks it down into and through the adjacent channel, thereby effecting 5 the folding of such end, and carrying the fold through and just beyond the opposing link of the intermittently movable carrier.

The two blades 29 are borne by arms 30 which are mounted on and concurrently operated by a 10 rock-shaft 31 having its bearings in brackets 32 rising from the table. Fast on the rock-shaft 31 is a gear sector 33 in mesh with a similar sector 34 fast on a rearward parallel rock-shaft 35 having its bearings in the walls of the slotted body 15 portion 36 of a standard 37 which rises from the table. The shaft 35 is encircled by a torsional spring 38, whereof one end is secured to the shaft 35 and the other end to a crank arm 39 loose on such shaft. This crank arm has a lateral stud or 20 projection 40 which is normally urged by the action of the spring in contact with a toe 41 fast on the shaft 35. The crank arm 39 is connected by means of a link 42 with a rocker-arm 43 bearing a roll 44 which runs in the race of a cam 45 25 fast on the driven cam shaft 19 of the machine. The contour of the cam race is such as to effect through the connections just described oscillatory motion of the rock-shaft 35, thus through the agency of the meshing sectors 33 and 34 oscillating the folding blades.

When the blades are up the slides are pushed endwise toward each other to carry the imposed covers and locate the rearwardly projecting ends of the latter directly under the blades, which 35 blades then descend upon the opposing ends of the covers. The slides then remain at rest for an interval and move back toward the magazines. When the slides are about half way back the folding blades have reached their extreme down 40 position. In the next or return stroke of the blades the slides continue back to their original position under the magazines in readiness to push forward the next succeeding covers. The portion of the carrier supported on the table is inter- 45 mittently driven to present two of the links to the open ends of the respective channels 28 of the folding members 27 in timed relation to the operation of the folding blades so as to receive the end folded covers.

50 The mechanisms thus far described are set out in detail in the patents previously mentioned.

In the preferred form of my invention as herein illustrated the acting end 46 of each of the blades 29, as well as the complementary folding 55 channel therefor, corresponds in width, or substantially so, with that of the friction bearing base (B) to be imparted to the cover, such acting end of the blade being longitudinally grooved, as at 47. Mechanisms are provided whereby re- 60 inforcing material is positioned above the respective covers and in the paths of the blades preparatory to the effective folding strokes of the latter, to the end that during such strokes opposing reinforcing strips (S) are inserted in 65 the folded portions of the covers and are introduced therewith into the links of the carrier. The blades with their expanded acting ends constitute forming plungers.

As the mechanisms referred to are alike in construction and operation a description of one will suffice, as follows:

Forwardly of each of the channeled folding members 27 is a housing comprising a standard 48 which is bolted to the table, and which stand- 75 ard is formed with a wall portion 49 extending

toward the channeled member. The top of the wall is in the same plane, or substantially so, as the top of the channeled member. A side wall 50 having an extension 51 is arranged in spaced parallel relation to the standard and its extension, the whole being connected by integral cross-members 50. The standard 48 and wall 50 are connected by a bridge piece 52, and the lower end of wall is connected to the standard by a foot-bar 53. Supported on the cross-member 50 is a horizontal bed 54 the rearward end of which overhangs the forward wall of the folding channel 28, and is recessed in its under surface, as at 55, to permit the free passage of the cover over the folding channel and in the 15 downward path of the folding blade. (See Figs. 4, 5 and 6.)

The shafts 56 of a pair of co-acting feed rolls 57 having their bearings in the forward part of the housing are arranged to receive between them a web (W) of material such as cardboard, the same width as a match cover, or substantially so, which rolls intermittently advance the web along the bed and toward the folding channel.

In the present instance the feed roll shafts are 25 equipped at one end with meshing gears 58, the upper shaft having thereon a ratchet 59 with the teeth of which engages an actuating pawl 60. The pawl is carried by a rock-lever 61 which is loose on the shaft 56 and is operatively connected by means of a rod 62 with the strap 63 of an eccentric 64 fast on a shaft 65 having a bearing in the lower portion of the standard 48. Fast on the shaft 65 is a sprocket wheel 66 which is connected by means of a chain 67 with a similar wheel 68 on the shaft 19. Hence during the operation of the shaft 19 the pawl lever 61 is actuated to effect a regular intermittent rotation of the feed wheels and perforce corresponding step-by-step advancement of the web. (See Figs. 40 1 and 4.)

In each step of the web (W) after it leaves the feed-rolls the web is partially severed or weakened transversely thereof to provide a succession of connected sections suitable for reinforcing strips (S); that is, each line of severance *x* is interrupted by small frangible connecting portions *y*. (See Figs. 7 and 8.) In the present instance the partial severance of the web is effected by the action thereon of a vertically-reciprocating cutter blade 69 which overhangs the path of the web rearwardly of the feed-rolls. As seen in Fig. 7 the acting edge of the cutter is interrupted by spaced recesses 70 forming non-cutting portions. A suitably-disposed anvil or 55 backer bar 71 for the web is arranged in the bed directly under the cutter.

As herein illustrated the cutter blade is af- 60 fixed to a cross-head 72 which is slidably fitted in vertical guide ways 73 in the housing. The upper end of the cross head is provided with lugs 74 that are pivotally and slidably connected to a lever arm 75 fast on a transverse shaft 76 journaled in lugs 77 on the bridge piece 52. Also fast on the shaft 76 is a lever arm 78 which is 65 connected by means of a rod 79 with the strap 80 of an eccentric 81 fast on the driven shaft 65 previously referred to, which eccentric effects through the connections just described the re- 70 ciprocation of the cutter in timed relation to the operation of the web-feeding rolls 57.

Mounted on the cross-head 72, in co-operative relation to the cutter, is a stripper which is effective to hold down the web during the operation of the cutter. In the present instance the 75

stripper comprises a bar 82 slidably fitted in a vertical guide-way 83 in the face of the cross-head adjacent the cutter. The lower end of the bar is in the form of a T-head 84 to provide an 5 extended bearing surface which is yieldingly urged toward and against the top of the web by the action of a compression spring 85 interposed between a laterally projecting lug 86 on the top of the bar 82 and a similar lug 87 fast on the 10 cross-head. (See Fig. 7.) The bar 82 has therein a vertical slot 88 into which extends a limiting pin 89 fast on the cross-head.

The partially severed web progresses to and past the periphery of a glue applying device 15 which extends through an opening 90 in the bed and applies glue (g) to the succeeding strip sections. In the present instance the device comprises three spaced glue-applying disks 91 having a common hub 92 fast on a shaft 93 which 20 has its bearings in boxes 94 mounted in the rearward extension 49 of the housing. On one end of the shaft is a gear 95 which is intermittently driven through an idler gear 96 in mesh with the gear 58 of the lower feed roll 56. The 25 disks in their rotation dip into the contents of a suitable glue containing vessel 97 which is mounted on a supporting structure 98 on the table 16, thus progressively carrying up the glue and applying it to the opposing surface of the 30 travelling web. The web is held in contact with the disks 91 by means of an overhanging pressure roll 99, the shaft 100 of which is slidably and rotatably mounted in spaced slotted bearings 101 on the bed 54. This shaft has thereon 35 a gear 102 in mesh with the driven gear 85 of the glue wheel shaft, the ratio of the gearing in the train between the pressure roll and the feed rolls being such as to rotate the pressure roll and the glue wheel at proper speed.

40 Slidably mounted on the foot bar 53 of the housing are scraper blades 103 having their inner or acting ends in cooperative relation with the peripheries of the respective disks 91 so as to regulate the thickness of the films of glue that 45 are carried up to the web by the disks. The outer end of each blade has a depending slotted lug 104 through which freely extends the shank of a set screw 105 that is threaded into the foot bar, a compression spring 106 being interposed between the bar and the lug. By properly manipulating its set-screw any scraper blade can be nicely adjusted in respect to the glue applying disk. The disks in conjunction with the roll 99 serve as an auxiliary feed to advance the partially severed web and position each succeeding 50 leading strip section over the folding channel and in the path of the descending folding blade.

The upper surface of the bed 54, in the area thereof between the glue wheel and the folding 60 channel, is provided with parallel longitudinal grooves 206 located in line with the respective disks 91, which grooves afford free channels for the glue on the under side of the web. (See Figs. 2, 5 and 6.)

65 Hold-down means for the web in its progress from the cutter to the folding channel is provided, such means, in the form shown, comprising two spaced cross-bars 107 and 108 which are secured to lateral flanges 109 on the bed, the bar 107 being located between the cutter and the rolls, and the bar 108 between the rolls and the folding channel. On the bars 107 and 108 are supported longitudinal strips 110 and 111 respectively, which strips are in alignment with the 70 spaces between the respective disks 91.

From the foregoing it will be seen that in the intermittent travel of the web the leading strip section, partially severed from the web and supplied with glue on its under surface, is positioned directly over the adjacent end of the flat book 5 cover that is seated at the mouth of the folding channel 28 and across the downward path of the folding blade. Thereupon, during the dwell of the strip, the grooved lower end of the descending blade strikes the opposing strip, separates it from the web, and pushes the strip and the opposing cover through the folding channel, thus folding the leading end portion of the cover and carrying it with its associated reinforcing strip into and through the carrier link. This 10 done, the blade resumes its raised position and a succeeding strip section is advanced into the path of the blade in the next following down stroke thereof, and so on.

It is to be noted that the concave cross-section 20 of the acting end of the folding blade not only affords a thin longitudinal cutting edge, as at 112, to effect the easy severance of each strip section presented thereto, but it also co-acts with a suitably-disposed complementary convex abutment 113 located rearwardly adjacent the path of the chain, thus imparting to the reinforced base of the cover fold when it has been forced through the chain link a concavo-convex formation which ensures straight and well-defined longitudinal edges for the base when the latter assumes a flat condition following the passage of the cover from the abutment. As illustrated the abutment is yieldingly supported by an upstanding spring strip 114 which is clamped to a suitably-disposed bar 115 at the rear of the table 16. Where, as in the present instance, two book covers are introduced in the chain a longitudinally extending cam member 116 is interposed between the two spaced abutments so that in the travel 35 of the chain, after the insertion of the covers therein, the folded end of the trailing cover will be pushed slightly toward the chain by the opposing beveled end of the cam in a manner to clear the abutment for the leading cover. The 40 cam member 116 is formed on or supported by the horizontal member of an angle-piece 117 which is bolted to the standard 31. (See Figs. 2 and 4.)

It is to be understood that the invention is not limited to the particular exemplifying form 50 thereof herein disclosed, as the mechanisms may be modified within the principle of the invention and the scope of the appended claims.

I claim:

1. In a booking machine, the combination with 55 cover folding means including a forming plunger, means for supplying covers across the path of said plunger, and means for imposing reinforcing strips on the respective covers and in the effective path of the plunger, whereby in each folding and forming stroke of the said plunger a reinforcing strip is introduced flatwise in the fold of the cover.

2. In a booking machine, the combination with 60 cover folding means including a forming plunger, means for supplying covers across the path of said plunger, and means for feeding a web of reinforcing material to present successive leading end portions thereof to the respective covers 65 and in the effective path of the plunger, whereby in each folding and forming stroke of the said plunger the opposing leading end portion is severed from the web and introduced flatwise in the fold of the cover.

3. In a booking machine, the combination with cover folding means including a forming plunger, means for supplying covers across the path of said plunger, means for feeding a web of reinforcing material to present successive leading end sections thereof to the respective covers and in the effective path of the plunger, and means for weakening the web transversely at determined intervals to define the said sections, whereby in each folding and forming stroke of the said plunger the opposing leading end section is severed from the web and introduced flatwise in the fold of the cover.
4. In a booking machine, the combination with cover folding means including a forming plunger, means for supplying covers across the path of the plunger, means for feeding a web of reinforcing material to present successive leading end sections thereof to the respective covers and in the effective path of the plunger, a cutter for partially slitting the web transversely at determined intervals to define the said sections, a stripper element supported in close relation to said cutter, and means for actuating said cutter and stripper element in timed relation to the feeding means.
5. In a booking machine, the combination with cover folding means including a forming plunger, means for supplying covers across the path of said plunger, means for feeding a web of reinforcing material to present successive leading end sections thereof to the respective covers and in the effective path of the plunger, said feeding means including a member for applying glue to one side of the web and a pressure member for the opposite side of the web, a cutter for partially slitting the web transversely at predetermined intervals to define the said sections, and means for actuating said cutter in timed relation to the web feeding means.
6. In a booking machine, the combination with cover folding means including a forming plunger, means for supplying covers across the path of said plunger, means for feeding a web of reinforcing material to present successive leading end sections thereof to the respective covers and in the effective path of the plunger, said feeding means including a discal element for applying glue to one side of the web, a pressure member for the opposite side of the web, and means for actuating the discal element, a cutter for partially slitting the web transversely at determined intervals to define the said sections, and means for actuating said cutter in timed relation to the feeding means.
7. In a booking machine, the combination with cover folding means including a forming plunger, means for supplying covers across the path of said plunger, means for feeding a web of reinforcing material to present successive leading end sections thereof to the respective covers and in the effective path of the plunger, said feeding means including a discal element for applying glue to one side of the web, a pressure member for the opposite side of the web, and means for actuating the discal element, a cutter for partially slitting the web transversely at determined intervals to define the said sections, a stripper element supported in close relation to said cutter, and means for actuating said cutter and stripper element in timed relation to the feeding means.
8. In a booking machine, the combination with cover folding means including a forming plunger, means for supplying covers across the path of said plunger, means for feeding a web of reinforcing material to present successive leading end sections thereof to the respective covers and in the effective path of the plunger, said feeding means including two feeding units arranged one in advance of the other and means for actuating said units in timed relation whereby the first unit feeds the web to the second unit and the latter unit feeds the web to the path of the plunger, a cutter for partially slitting the web transversely at determined intervals to define the said sections, said cutter located adjacent the second feed unit, and means for actuating said cutter in timed relation to the feeding means.
9. In a booking machine, the combination with cover folding means including a forming plunger having a concave acting portion, a convex abutment with which said concave portion co-acts at the end of the folding and forming stroke of the plunger, means for supplying covers across the path of said plunger, and means for imposing reinforcing strips on the respective covers and in the effective path of the plunger.
10. In a booking machine having a carrier for folded covers, the combination with said carrier of cover folding means including a forming plunger having a concave acting portion, and a convex abutment rearwardly adjacent the carrier and in the path of the said concave portion when the plunger reaches the end of its folding and forming stroke.

WILMER C. NICODEMUS.
